DESIGN FOR A TEXTILE FABRIC OR SIMILAR ARTICLE

David V. Villasenor, Los Angeles, Calif., assignor to Lester G. Griffith, Los Angeles, Calif.

Application November 3, 1939, Serial No. 88,028

Term of patent 3½ years

all whom it may concern:

Be it known that I, David V. Villasenor, a citizen of the United States, residing at Los Angeles, County of Los Angeles, State of California, have invented a new, original, and ornamental Design for a Textile Fabric or Similar Article, of which the following is a specification, reference being had to the accompanying drawing, forming part hereof.

The figure is a plan view of a repeat in a textile fabric or similar article, showing my new design, the dash lines indicating the borders of the running repeat.

I claim:

The ornamental design for a textile fabric or similar article, substantially as shown and described.

DAVID V. VILLASENOR.
